FUEL TRANSPORT TRAILER

Frederick J. Kunz, Fort Jennings, Ohio, assignor
to Gramm Trailer Corporation, Delphos, Ohio,
a corporation of Ohio

Application December 2, 1950, Serial No. 13,244

Term of patent 14 years

(Cl. D14—3)

To all whom it may concern:

Be it known that I, Frederick J. Kunz, a citizen of the United States and a resident of Fort Jennings, Putnam County, Ohio, have invented a new, original, and ornamental Design for a Fuel Transport Trailer, of which the following is a specification, reference being had to the accompanying drawing, forming a part thereof.

In the drawing:

Figure 1 is a front perspective view of the fuel transport trailer showing my new design;

Figure 2 is a top plan view of the fuel transport trailer;

Figure 3 is a rear end elevation of the fuel transport trailer; and

Figure 4 is a side elevation of the fuel transport trailer with the wheels retracted or elevated for use as a sled.

I claim:

The ornamental design for a fuel transport trailer, as shown.

FREDERICK J. KUNZ.
